(57) **CLAIM**

The ornamental design for a television receiver as shown and described.

DESCRIPTION

FIG. 1 is a front, top, right perspective view of a television receiver showing our new design, wherein the legs are in the first positions;

FIG. 2 is a rear, top, right perspective view thereof; FIG. 3 is an enlarged front, top, right perspective view of a portion of the television receiver shown within the area designated as **3** in FIG. 1;

FIG. 4 is an enlarged rear, top, right perspective view of a portion of the television receiver shown within the area designated as **4** in FIG. 2;

FIG. 5 is a front elevational view thereof;

FIG. 6 is a partially enlarged front elevational view of a portion of the television receiver shown within the area designated as **6** in FIG. 5;

FIG. 7 is an enlarged front elevational view of a portion of the television receiver shown within the area designated as **7** in FIG. 5;

FIG. 8 is a cross sectional view of the television receiver taken in the direction of line **8-8** of FIG. 5;

FIG. 9 is an enlarged cross sectional view of a portion of the television receiver shown within the area designated as **9** in FIG. 8;

FIG. 10 is an enlarged cross sectional view of a portion of the television receiver shown within the area designated as **10** in FIG. 8;

(Continued)

FIG. 11 is an enlarged cross sectional view of a portion of the television receiver shown within the area designated as 11 in FIG. 9;

FIG. 12 is an enlarged cross sectional view of a portion of the television receiver shown within the area designated as 12 in FIG. 10;

FIG. 13 is a left side elevational view of the television receiver;

FIG. 14 is a right side elevational view thereof;

FIG. 15 is an enlarged left side elevational view of a portion of the television receiver shown within the area designated as 15 in FIG. 13;

FIG. 16 is an enlarged right side elevational view of a portion of the television receiver shown within the area designated as 16 in FIG. 14;

FIG. 17 is a top plan view of the television receiver;

FIG. 18 is an enlarged top plan view of a portion of the television receiver shown within the area designated as 18 in FIG. 17;

FIG. 19 is an enlarged top plan view of a portion of the television receiver shown within the area designated as 19 in FIG. 17;

FIG. 20 is an enlarged top plan view of a portion of the television receiver shown within the area designated as 20 in FIG. 17; and,

FIG. 21 is an enlarged top plan view of a portion of the television receiver shown within the area designated as 21 in FIG. 17.

The broken lines illustrating portions of the television receiver form no part of the claimed design. The dot-dash broken lines illustrating boundaries of the claimed design form no part of the claimed design. The rear portions of the television receiver shown in faded tone within the perimeter of the even dash broken lines in FIGS. 2, 13 and 14 form no part of the claimed design.
